UNITED STATES PATENT OFFICE.

GERHARD P. HELMERS, OF BALTIMORE, MARYLAND.

CUFF.

1,143,626.

Specification of Letters Patent. Patented June 22, 1915.

Application filed August 29, 1914. Serial No. 859,163.

To all whom it may concern:

Be it known that I, GERHARD P. HELMERS, a citizen of the United States, residing at Baltimore city, State of Maryland, have invented certain new and useful Improvements in Cuffs, of which the following is a specification.

This invention relates to cuffs for shirts and like garments and more particularly to 10 the arrangement of the button holes in such cuffs.

Cuffs are fastened by means of cuff buttons engaged in button holes in both of the overlying layers of the cuff, said overlying 15 layers consisting of the ends of the cuffs. The button holes in these ends of the cuffs have almost universally been arranged so that they lie parallel with the edges of the cuff, and when these ends of the cuff are laid 20 one upon the other, the button holes in each layer coincide with those of the other so that when the small or inner end of the cuff button has been passed through such coinciding button holes, said holes are substantially a 25 single hole, that is to say, when the holes thus coincide, and the small end of the button slips through one of them, there is nothing to prevent the end of the button slipping through the coinciding button hole of 30 the overlying end of the cuff, and the button is thereby, very often lost beyond recovery.

The primary object of this invention is to provide simple and economical means for overcoming this difficulty and in carrying 35 out this object, the invention consists primarily in the provision of button holes in the ends of cuffs and the like, arranged with relation to each other so that when the ends of the cuffs are overlaid for the insertion of 40 the buttons, the button holes in said overlying ends will lie at an angle to each other, and will not coincide.

The invention further consists in the specific forms and arrangements of the cuff and 45 its button holes which will be hereinafter fully described and afterward specifically claimed.

In order that the construction and operation thereof may be readily comprehended, 50 an approved embodiment of the invention is illustrated in the accompanying drawings, in which—

Figure 1 represents a view in perspective of the end of a sleeve, with the wrist band 55 and cuff attached thereto and having their ends overlaid in the position they assume

when the cuff is secured to the wearer. Fig. 2 represents, in plan, the same parts, spread out flat, the drawing being upon a somewhat smaller scale than that of Fig. 1. Fig. 3 60 represents the same parts, on the same scale as in Fig. 2, the cuff being overlaid on the wrist band, but not folded over for the purpose of securing it on the wearer.

Like reference characters designate the 65 same parts wherever they occur in a plurality of the figures of the drawings.

Referring specifically to the drawings, 5 indicates what may be denominated the outer end of the sleeve to which is attached, 70 either integrally or by proper seams, what might be denominated the inner folds of the cuff but which, for the purposes of this specification, will be called the wrist band 6, while 7 designates the outer fold of the cuff 75 which for the purposes of this specification will be denominated simply the cuff.

Ordinarily the parts 6 and 7 are each provided near their ends with button holes which have generally been arranged in directions parallel to each other and to the outer edges of the cuff and wrist band. Sometimes the cuff has been worn in the position with relation to the sleeve as illustrated in Fig. 2, though ordinarily the part will be 80 worn arranged as shown in Fig. 1. In either form, the old style of button holes, when the parts are folded over so that the ends of either the cuff as in Fig. 2 or the folded back cuff as in Fig. 1, will overlie each 85 other, and the button holes will coincide with each other but in carrying out my invention I have provided button holes 8 and 9 in the wrist band, and 10 and 11 in the cuff proper, all of which button holes lie in direction at 90 an inclination to the edges of the cuff, so that when the cuff proper is folded over on the wrist band, as shown in Figs. 1 and 3, and the cuff arranged as in Fig. 1 with the opposite ends of the cuff and wrist band 100 overlying each other, the button holes in the opposite ends of both the wrist band and cuff, will lie at an angle to each other, the only coinciding parts, being the ends of the holes as at 12 in Figs. 1 and 3, said 105 coinciding ends forming the apex of a V, the legs of which are represented by the main bodies of the button holes.

When the cuff button is inserted, as for instance from the outside, through overlaid 110 button holes 8, 9, 10 and 11, in the form of Fig. 1, the direction of the button holes

with relation to each other will be such that any strain tending to release the inner end of the button from the inner button hole, will be resisted by the edges of the overlying button hole, and even though the smaller head of the button hole should for any reason slip through the one button hole, the relative positions of this button hole with those superposed upon it, is such that there will be no tendency whatever for the said inner head of the button to slip through any of these superposed holes.

While I have specifically described the location and direction of the button holes as illustrated, I desire it to be understood that changes and variations may be made therein without departing from the spirit and scope of the invention as hereinafter claimed.

Having thus fully described my invention what I claim as new and desire to secure by Letters Patent of the United States is—

A wrist band having a cuff attached thereto and provided with a permanent folding

line therebetween whereby said cuff can be folded back upon the wrist band, said cuff and wrist band each being provided adjacent their ends with a button hole inclined relative to said folding line, said button holes in each respective part being inclined in opposite directions and corresponding button holes in respective ends being arranged parallel with each other with their outer terminals spaced an equal distance from the folding line and also from the edges of said ends, whereby, when the cuff is folded upon the wrist band, said corresponding button holes will lie in angular relation with respect to each other and to said folding line with their outer terminals in register and diverging backwardly toward the center of the cuff.

In testimony whereof I affix my signature in presence of two witnesses.

GERHARD P. HELMERS.
